CLAIM

I claim the ornamental design for a truck wash paddle, as shown and described.

DESCRIPTION

FIG. 1 is a front, top, and side perspective view showing my design for a truck wash paddle;

FIG. 2 is a front elevation view thereof;

FIG. 3 is a first side elevation view thereof;

FIG. 4 is a back elevation view thereof;

FIG. 5 is a second side elevation view thereof;

FIG. 6 is a top plan view thereof;

FIG. 7 is a bottom plan view thereof;

FIG. 8 is an enlarged front, top, and side perspective view showing my design for a truck wash paddle with a handle portion broken away;

FIG. 9 is an enlarged front elevation view thereof;

FIG. 10 is an enlarged side elevation view thereof;

FIG. 11 is an enlarged top plan view thereof; and,

FIG. 12 is an enlarged bottom plan view thereof.

The truck wash paddle is shown broken away in some figures for ease of disclosure only.

1 Claim, 4 Drawing Sheets
